Claude Raymond

UNITED STATES PATENT OFFICE.

JOSEPH WM. SMITH, OF NEWTON, MASSACHUSETTS.

SUSPENDER-END.

SPECIFICATION forming part of Letters Patent No. 624,557, dated May 9, 1899.

Application filed March 13, 1899. Serial No. 708,842. (No model.)

To all whom it may concern:

Be it known that I, JOSEPH WILLIAM SMITH, a citizen of the United States, residing at Newton, in the county of Middlesex and State of Massachusetts, have invented a new and useful Improvement in Suspender-Ends, of which the following is a full, clear, and exact description, reference being had to the accompanying drawings, forming a part of this specification, in explaining its nature.

The invention relates to the herein-described improvement in suspender-ends whereby certain advantages in strength of construction and wearing properties are obtained and the size of the cast-off reduced and made more ornamental.

The invention will be more fully described in connection with the drawings, wherein—

Figure 1 is a view in elevation of a suspender-end constructed in accordance with my invention. Fig. 2 is a view, enlarged, taken through the parts on the dotted line 3 3 after they have been assembled, but before they have been united. Fig. 3 is a view, enlarged, upon the dotted line 3 3 after the parts have been united, but with the cast-off represented as disengaged from its holding-stud. Fig. 4 represents in elevation my invention applied to the back button end. Fig. 5 is a section thereof upon the line 5 5 of Fig. 4. Fig. 6 illustrates a modification to which reference is hereinafter made.

The invention has for its object two features, one comprising a metal housing or frame connecting the button end with the strap end and through which the button end renders and the other of which comprises the same housing or frame provided with a hook to engage the cross-bar of a metal loop at the suspender-strap end and further provided with a cast-off and, if desired, a drawers-supporter.

Referring to the drawings, A represents the front end of a suspender-strap. a is a metal loop carried by said end and having a cross-bar a', which is narrower than said end and which connects the lower ends of the depending sections a² of said metal loop, and which cross-bar is adapted to be engaged by the hook b of the metal housing B of the button end and also the flexible cast-off tongue C of said button end. The metal housing b is

preferably made from a flat metal blank of suitable length and edge configuration, which is bent at the center of its length, has its sides separated to form a space or cavity b' open at both ends, and portions above the cavity brought together to form the neck b² and hook b. It has also in its sides the holes b³, which are in line with each other and through which a stud or rivet D extends. There is mounted upon this stud or rivet in the space or cavity b' an eyelet d, which holds the sides of the housing apart. The stud or rivet D binds the sides together against the flanges of the eyelet and also serves to fasten the flexible casing c to the metal housing and the stud member E of the cast-off to the flexible casing and metal housing, the flange d' of the stud or rivet abutting against the flexible casing c upon one side of the housing and the opposite end d² of the stud or rivet being upset in the cavity e of the ball member of the cast-off, causing the flange e' of the ball member to bear against the casing c and the side of the housing opposite that against which the flange d' bears.

When used in connection with a front button end, the flexible casing c may be extended below the metal housing to form a loop C' for the drawers-holder F, the cord f of said drawers-holder passing through the loop. (See Figs. 1 and 3.) The flexible casing when used with a front button end also has its upper end extended to form the flexible cast-off tongue C, which extends about the hook b of the metal housing and has a socket member C² of a separable fastener, which is located to engage the ball member E, and thus close the opening b⁴ to the mouth of the hook b. The metal housing is represented as combined with a button end G, which consists of a cord formed into a long loop and having near its ends metal clasps g g', uniting them together and one of which also unites the ends of the cord and which also form the buttonholes g² g³. The sections g⁴ g⁵ of the cord between the clasps are substantially parallel, the outer one being somewhat longer than the inner and in attaching the button end to the housing I prefer to pass one end of it through the cavity of the housing, to then separate the sections g⁴ g⁵ of the cord in the housing by the eyelet d, and to then simultaneously unite

the casing *c*, sides of the metal housing, and the ball member *E* of the fastener together by passing the rivet or stud *D* through the holes in the casing, housing, and eyelet, and upsetting its end in the cavity of the ball. The parts assembled prior to this final fastening are represented in Fig. 2 and as fastened in Fig. 3.

If the drawers-holder is used, it is slipped upon the loop *C'* of the flexible casing before it is fastened to the housing, so that the single act of setting the stud or rivet secures the drawers-holder and button end in place, attaches the flexible case to the metal housing, ties the two sides of the metal housing together, secures the eyelet in position therein, and attaches the ball or stud member of the cast-off to the housing and casing. The complete suspender-end is then provided with a metal holder in which the button end may render and which holds or supports the button end securely and which also attaches the button end to the suspender-strap, thereby not only providing a very strong union between the end of the suspender-strap and the button end, but one that will outwear either and one which is also very light in appearance and weight, while it is held from accidental detachment from the suspender-end by the flexible cast-off tongue *C*, the office of which is to close the mouth of the hook *b* and form a finish. As this cast-off does not take the strain of the button-head, it may be narrower and lighter than the usual type of cast-off which does. The strain upon the casting-loop *C'* will be taken by the metal housing through the stud or rivet.

In Fig. 6 I have represented a slight modification in that the flexible casing *c* conforms to the lower end of the metal housing and is not adapted to form a loop for engaging the drawers-suspender.

In Figs. 4 and 5 I have represented my invention as modified to attach the back button end to the suspender-straps. The metal housing *B* in this modification is unprovided with a hook at its upper end, but is there made straight. The flexible casing surrounding the housing does not form a cast-off, but is a loop of strong material, like leather, surrounding the metal housing and uniting it to the joined ends of the suspender-straps *A A'*. There is no cast-off, and the stud or rivet unites the casing and metal housing in the same way that the stud above described acts, and it also holds the spacing-eyelet in the same manner. As it does not attach a ball member of a separable fastener, it may be and preferably is made in the form of a long tubular rivet, one end of which has a preformed flange and the other end of which is upset upon the flexible casing.

It will be seen that the lower part of the metal housing is integral and forms a loop or hanger for receiving and holding the lower cord or section of the button end *G* and one in which the cord may slide laterally. It will

also be seen that the upper cord of the button end extends through the housing over the eyelet and is held or supported by it and that the eyelet and the fastening-stud serve to separate the two parts or sections of the button end.

It will further be seen that the metal housing is jointless throughout its length, and this adds to the strength of the construction and to the cheapness of manufacture.

The principal use of the eyelet is to hold the two sides of the housing apart during the setting of the fastening-stud, and in some instances a removable spacing-piece may be used for thus maintaining the shape of the housing in lieu of said eyelet, in which case the fastening stud or eyelet itself separates the housing into its two chambers and is the sole means for dividing the two cords or parts of the button end.

Having thus fully described my invention, I claim and desire to secure by Letters Patent of the United States—

1. A suspender-end having a metal housing to engage or support the buttonhole ends or straps provided with a cast-off hook to engage a cross-bar on the suspender-end and a flexible cast-off tongue and means for engaging it with the metal housing in a manner to close the opening to the hook.

2. A suspender-end having a metal housing to support or engage the button ends or straps, provided with a cast-off hook, a flexible casing surrounding the metal housing and having a tongue forming a flexible cast-off, the said tongue having means whereby it is detachably engaged to the casing and metal housing in a manner to cover the mouth of the hook.

3. A suspender-end having a metal housing, button ends or straps engaged by said housing, a metal hook at the upper end of said housing, a flexible case surrounding said housing and forming below said housing a loop, and also providing over said hook a tongue, means for detachably securing said tongue to the casing and metal housing and a drawers-supporter engaged by said casing-loop.

4. A suspender-end having a metal housing, button ends or straps engaged by said housing and adapted to slide therein, a metal hook at the upper end of said housing, a flexible casing surrounding the housing, having a tongue forming a flexible cast-off, the said tongue having means whereby it is detachably secured to the casing and metal housing in a manner to cover the mouth of the hook.

5. A suspender-end having a metal housing provided with a cross-cavity open at both sides and divided into two sections or parts by a rivet or piece extending across the cavity to form upper and lower supports or bearings for the button end, and a button end having two parts *g⁴*, *g⁵*, the first of which is supported by the upper bearing and the second by the lower bearing, the two parts being also arranged to slide upon their bearings.

6. A suspender-end having a metal housing provided with a cross-cavity open at both sides and separated into two parts by a rivet or stud extending across the cavity, whereby 5 upper and lower bearings for the two sections of the button end are obtained, said button end, one section of which is held by the lower bearing and another section by the upper bearing, and a cover or case of flexible material surrounding said metal housing and secured thereto.

7. A suspender-end having a housing made of a single piece of metal bent to form a cross-cavity open at both ends and also provided 15 with holes for the reception of a fastening-stud or eyelet, a flexible casing surrounding said housing and also having holes in line with the holes of the housing, an eyelet or spacing-piece contained in the cavity of the 20 housing and separating it into two parts, a stud or eyelet extending through the holes of the casing and housing and uniting them together, and the sections of a button end passing through the cavity of the housing and 25 separated from each other by the eyelet and stud.

8. A suspender-end having a metal housing made of a single piece of metal formed to provide a cross-recess open at both ends, and a

hook, holes in the housing opposite each other, 30 a spacing-piece or eyelet contained in the chamber or cavity of the housing, a flexible casing surrounding the housing having an extension forming a cast-off or tongue, holes in said flexible casing in line with the holes of the 35 housing, a member of a detachable fastener and a stud or eyelet fastening the casing, housing, eyelet and member of the detachable fastener together and another member of a detachable fastener carried by said tongue 40 or cast-off and a button end having cords or sections extending through the housing, separated by the eyelet or fastening-stud.

9. The combination of the strap having the metal loop a provided with the cross-bar a' 45 and ends a^2 , with the suspender-end comprising a metal housing having a hook at the upper end to engage said cross-bar, a flexible casing surrounding the metal housing having a tongue or cast-off adapted to extend over the said bar and cover the mouth of the hook and also adapted to be detachably secured to the housing and casing, and button ends or straps engaged by said metal housing.

JOSEPH WM. SMITH.
